UNITED STATES PATENT OFFICE

2,369,888

ATTACHMENT FOR THE STEAM HEAT CONDUIT CONNECTIONS OF RAILROAD CARS

William Edwin Fronk, Ogden, Utah, assignor of
one-half to P. E. Carroll, Ogden, Utah

Application May 6, 1943, Serial No. 485,912

1 Claim. (Cl. 285—57)

The present invention relates generally to the steam heat conduit connections of railroad cars and has for its primary object to provide, in a manner as hereinafter set forth, novel means for automatically uncoupling such connections when the cars separate.

Another very important object of the invention is to provide an attachment of the aforementioned character which is adapted to hold up or support the conduits after they have been uncoupled.

Other objects of the invention are to provide an automatic uncoupling attachment of the character described which will be comparatively simple, strong, durable, highly efficient and reliable in operation and which may be manufactured and installed at low cost.

All of the foregoing and still further objects and advantages of the present invention will become apparent from a study of the following specification, taken in connection with the accompanying drawings wherein like characters of reference designate corresponding parts throughout the several views, and wherein:

Figure 1 is a view in side elevation, showing an attachment constructed in accordance with the present invention installed.

Figure 2 is a top plan view thereof.

Figure 3 is a top plan view, showing one of the sections of the connecting head after the conduits have been uncoupled.

Figure 4 is a view in side elevation, showing the invention installed on another connection.

Referring now to the drawings in detail, and to Figures 1, 2 and 3 thereof in particular, it will be seen that reference numeral 1 designates generally a pair of steam heat connections which are mounted on the ends of railroad cars. The connections 1 include the usual vertical conduits 2 which are hingedly connected at their upper ends, as at 3, to the usual members 4. Horizontally extending conduits 5 are hingedly connected at 6 to the lower end portions of the conduits 1 for swinging movement in a vertical plane, said conduits 5 including sections 7 which are swivelly mounted thereon, as at 8. The sections 7 of the conduits 5 are coupled by the usual connecting head 9. The head 9 includes complementary members 10 having locking bars 11 pivotally mounted thereon at an intermediate point.

The present invention comprises chains 12 of suitable length having one end connected to one end portion of the locking bars 11 at 13. The other ends of the chains 12 are connected at 14 to the vertical conduits 2 adjacent the hinges 3 thereof.

It is thought that the operation of the invention will be readily apparent from a consideration of the foregoing. Briefly, when the cars are

uncoupled and separate, the connections 1 are pulled upwardly and tend to straighten out, as suggested in dotted lines in Figure 1 of the drawings, the conduits 1 and 5 swinging on the hinges 3 and 6. In this manner the slack is taken out of the chains 12. As the cars continue to separate the chains 12, after the slack has been removed therefrom, actuate the bars 11 for unlocking the members 10. As the cars continue to separate from this point, the chains 12 raise and uncouple the members 10 of the head 9.

In the connection shown in Figure 4 of the drawings, the vertical conduits 15 are coupled to the members 16 by ball and socket connections 17. A substantially similar connection 18 couples the horizontal conduit 19 to the lower end portion of the vertical conduits 15. The same head 9 shown in Figures 1, 2 and 3 of the drawings, detachably connects the conduits 19. In this arrangement, the chains 12 are connected, at one end, by clamps or bands 20 to the upper portions of the vertical conduits 15. In other respects this form of the invention is substantially similar in construction and operation to the embodiment shown in Figures 1, 2 and 3 of the drawings.

It is believed that the many advantages of an automatic uncoupling attachment constructed in accordance with the present invention will be readily understood and although preferred embodiments are as illustrated and described, it is to be understood that further modifications and changes in the details of construction may be resorted to which will fall within the scope of the invention as claimed. For example, cables or the like may be substituted for the chains 12. Also suitable means other than those shown may be employed for connecting the ends of the chains or cables.

Having described the invention, what is claimed as new is:

The combination with a railroad car steam heat connection of the type comprising vertical and horizontal conduits hingedly mounted for swinging movement in a vertical plane and a head detachably connecting the horizontal conduits, said head including locking bars, of flexible members having one end connected to the locking bars and their other ends connected to the vertical conduits for actuating said bars to inoperative position and for swinging the head upwardly and uncoupling the same when the conduits are swung upwardly on their hinges, the points of connections of said flexible members to the vertical conduits being below the axes of swinging movement of said vertical conduits to provide for delayed uncoupling of the heads when said vertical conduits are swung upwardly.

WILLIAM EDWIN FRONK.
